(57) CLAIM

The ornamental design for a boating accessory, as shown and described.

DESCRIPTION

FIG. 1 is a perspective view of a boating accessory showing my new design;

FIGS. 2 and 7 views thereof;

FIG. 3 is a front view thereof;

FIGS. 4 and 5 are bottom and top views thereof; and, FIG. 6 is a back view of thereof.

The broken line showing of environmental structure in FIGS. 1–7 is for illustrative purposes only and forms no part of the claimed design.
